UNITED STATES PATENT OFFICE.

BLAGGOYA MRVOSH, OF ERIE, COLORADO.

AUTOMATIC CUT-OFF-VALVE.

Application filed April 21, 1923. Serial No. 633,816.

To all whom it may concern:

Be it known that BLAGGOYA MRVOSH, a citizen of the United States, residing at Erie, in the county of Weld and State of Colorado, has invented certain new and useful Improvements in Automatic Cut-Off Valves; and he does hereby declare the following to be a full, clear, and exact description of the invention, such as will enable others skilled in the art to which it appertains to make and use the same.

This invention relates to valve structures and more particularly to automatic cut-off valves for pipe systems and the like for conveying fluids such as liquids, steam or gases.

The object of the present invention is to provide an improved device for controlling a cut-off valve in such manner that the valve will be automatically and efficiently closed in the event and only in the event of a break in the pipe system or some other similar unforeseen accident permitting an abnormal flow of the fluid contents through the portion of the system in which the valve is located.

Further objects will more particularly appear in the course of the following detailed description.

The invention consists in the novel construction, arrangement and combination of parts as hereinafter particularly described and claimed.

Three sheets of drawings accompany this specification as part thereof, in which like reference characters indicate similar parts throughout.

Figure 1 is a plan view of the improved device with the cover removed;

Fig. 2 is a vertical longitudinal sectional view taken on line 2—2 of Figure 1;

Fig. 3 is a vertical transverse sectional view taken on line 3—3 of Figure 1;

Fig. 4 is a vertical transverse sectional view taken on line 4—4 of Figure 1;

Fig. 5 is a fragmentary transverse vertical section taken on line 5—5 of Figure 1;

Fig. 6 is a fragmentary vertical longitudinal view taken on line 6—6 of Figure 1.

Fig. 7 is a detailed view of valve 9.

In accordance with the present invention a suitable housing is provided preferably in the form of a casting, embodying a conduit 1, below a chamber 2, the former adapted to be associated in alignment and in continuity with a pipe system for the conveyance of fluids, such as liquids, steam or gases. The conduit 1 is adapted to be closed as by slide

gate valve 3 which is associated with a stem 3^a slidably mounted in suitable bearings provided in the frame, the stem 3^a being formed adjacent its upper end with rack teeth 27 adapted to be engaged by a pinion 4.

In the frame adjacent slide gate 3 is provided a cylinder 6 in which operates a piston 6^a provided adjacent its upper end with rack teeth 28 adapted also to engage the teeth of pinion 4 diametrically opposite the stem 3^a. The cylinder 6 communicates with conduit 1, and is controlled with respect thereto by a slide valve 7. An exhaust passage 8 is provided in the frame communicating with cylinder 6 controlled by a slide valve 9. With the structure thus far enumerated, and referring to Fig. 2, it will be noted that when the slide gate 3 is elevated piston 6^a will be correspondingly lowered in cylinder 6 and that when in this position the opening of slide valve 7 will permit the pressure of the fluid contents of conduit 1 while operating on piston 6^a to raise the same, thus rotating pinion 4 and lowering stem 3^a and thus closing slide gate 3 and closing the conduit.

Adjacent slide gate 3, but on the opposite side thereof with respect to the cylinder 6 is provided a housing for a suitable impact wheel 10 the vanes 10^a of which are adapted to project at one circumferential point within conduit 1, as is well illustrated in Fig. 3. The impact wheel 10 is secured to a vertical shaft 11 to the upper end of which is secured a bevel gear 29 adapted to mesh with a second bevel gear 30 secured to a horizontally mounted shaft 12 which is provided with a worm thread 31 having a pitch and lead which will operate in both directions adapted to mesh with a gear 13 mounted on a horizontally disposed shaft 14 arranged at right angles with shaft 12. Shaft 14 carries a bevel gear 15 adapted to mesh with the second bevel gear 32 secured to a vertically mounted shaft 16 to the upper end of which is secured a wheel or disc 18 provided with a single peripheral tooth 33. In alignment with, but spaced from the shaft 14 is another shaft 20 having on one end a gear 19 the teeth of which are adapted to be engaged by the single peripheral tooth 33 of wheel 18 as is indicated in Fig. 2.

Secured to shaft 20 is one end of wound spring 21 the other end of which is adjustably secured as by screw 21^a to some suitable part of the frame. Also mounted on shaft 20 is a gear 22, the teeth of which are adapt-

ed to engage rack teeth upon a sliding rod 23 which is in turn pivoted to a lever 24 adapted to engage a bell crank lever 25 the other arm of which is connected to the slide valves 7 and 9.

The structure thus enumerated operates as follows:

The passage of the fluid contents through conduit 1 rotates by impact with vanes 10^a wheel 10 which, through gears 29 and 30 worm thread 31 and gears 13, 15 and 32 rotates wheel or disc 18. Each rotation of wheel 18 operates to partially rotate gear 19 by reason of engagement of the peripheral tooth 33 therewith. The rotation of gear 19 is, however, against the resistance of wound spring 21 which operates immediately upon the passage and disengagement of peripheral tooth 33 from gear 19 to return gear 19 to 20 its original position.

The various parts are so proportioned and arranged as to make this the normal, ordinary operation of the device. The parts are further so proportioned that the partial rotation of gear 19 will have no operative effect through gear 22, rack rod 23, bell crank 25, etc., upon the slide valves 7 and 9.

Upon any break in the pipe system, however, or any other cause producing an increased velocity in the fluid passing through conduit 1, the speed of rotation of wheel 10 will be greatly increased with a corresponding marked increase in the speed of wheel 18 by reason of which increased speed of rotation of wheel 18 the peripheral tooth 33 will reengage gear 19 before spring 21 can operate to return gear 19 to its normal position, with the result that gear 19 will be rotated by successive rapid impacts of the peripheral tooth 33 to give a pronounced longitudinal motion to rack rod 23 and thence through bell crank 25 to operate slide valves 7 and 9 to open slide 7 and close slide 9, thus permitting the pressure of the fluid in conduit 1 45 to operate upon the piston 6^a as previously described to close the slide gate 3.

The slide gate 3 having been thus automatically closed, the following structure is provided to reopen the gate:

50 The pinion 4 which is interposed between the valve stem 3^a and piston 6^a is mounted upon a spindle 36, upon one end of which is secured a strong wound spring 41 operative to wind upon the lowering of valve stem 3^a. 55 Upon the other end of spindle 36 is fixed a ratchet 37 adapted to be engaged by a dog 38 pivoted in lever 39 suitably pivoted to the frame as at 40 the lower end of which lever is formed to provide a connection between 60 the slide valves 7 and 9. This structure is

so arranged and proportioned that when the slide gate 3 has been lowered, as in Fig. 2, spring 41 will be tightly wound, and by reason of the operation of the slide valves 7 and 9 through bell crank 25 lever 39 will have been thrown upwardly as indicated in dotted lines in Fig. 5, the dog 38 permitting the rotation of ratchet 37 as operated by pinion 4 but preventing its rotation in the opposite direction by spring 41.

It being desired to reopen gate 3, lever 39 would be pulled back to the position illustrated in full lines in Fig. 5, whereupon, slide valve 7 would be closed and slide valve 9 would be open, permitting the escape of the contents of cylinder 6 through port 8, and also permitting rotation of ratchet 37 by reason of the force of spring 36, thus rotating pinion 4 to raise valve stem 3^a, to lift slide gate 3.

Various modifications in the precise form and arrangement of parts will readily suggest themselves to those skilled in the art, but all within the scope of the present invention as claimed.

Having thus fully disclosed my invention, I claim:

1. An automatic cut-off valve comprising in combination a conduit, an impact device associated with the conduit and adapted to be operated by the passage of a fluid therethrough, a valve in the conduit, and means operated by the impact device for operating the valve, said last mentioned means including a lost motion device through which the normal operation of the impact device will not affect the valve but an abnormal speeding up of the impact device will operate the valve.

2. An automatic cut-off valve comprising in combination a conduit, an impact device associated with the conduit adapted to be operated by the passage of a fluid therethrough, a valve in the conduit and means operated by the impact device for operating the valve, said last mentioned means including a resiliently controlled gear and an intermittent contact for operating of said gear.

3. An automatic cut-off valve comprising in combination a conduit, a vaned wheel having vanes projecting into the conduit, a valve in the conduit and means for operating the valve including means responsive to pressure in the conduit and means controlling the application of said pressure to said operative means including a lost motion connection with said vaned wheel.

In testimony whereof I affix my signature.
BLAGGOYA MRVOSH.
